UNITED STATES PATENT OFFICE.

CHRISTIAN WINKLER, OF PORTLAND, OREGON.

KEY-SEATING MACHINE.

1,420,600.

Specification of Letters Patent. Patented June 20, 1922.

Application filed June 2, 1920. Serial No. 386,018.

To all whom it may concern:

Be it known that I, CHRISTIAN WINKLER, a citizen of the United States, and a resident of Portland, county of Multnomah, 5 State of Oregon, have invented a new and useful Improvement in Key-Seating Machines, of which the following is a specification.

This invention relates generally to machines for cutting keyways in the hubs of gears, pulleys, wheels, etc., and has particularly to do with an improved type of this class of machine.

The main object of my invention is to 10 provide a key-seating machine that will be simple and economical in construction, yet at the same time easy and capable in operation.

To this end, I have invented the machine 20 shown in the accompanying drawings, of which—

Fig. 1 is a perspective view of my machine;

Fig. 2 is a perspective view of details of 25 my machine, showing them in their inter-related positions;

Fig. 3 is a longitudinal section of my machine; and

Fig. 4 is a transverse section of the same. 30 In these drawings, *a* represents the frame of the machine. Said frame *a* has vertical sides *b*, the upper portions of which are formed with longitudinal grooves *b'* adapted to act as guideways.

35 A face plate *c* is pivotally fastened to the forward end of the frame by pivot pins *d* and clamp bolts *e*, the latter adapted to work in the circular slots *f*. This arrangement permits an angular adjustment of the face plate as suggested by the broken lines of 40 Fig. 3.

The face-plate *c* is provided with holes *g* which form means for clamping in position the piece to be worked on.

45 A member *h* is made with side shoulders *i*, an upper groove *j*, and a lower groove *k*, and the horizontal wall which forms the top of the groove *k*, is made with two slotted holes *l* and *l'*. The tool holder *m* is adapted to fit freely in the groove *j*, of the member *h*, and is pivotally fastened to said member by a fulcrum pin *n*.

55 Holes *o* are provided at the forward ends of the parts so that when desired to move the fulcrum, the pin *n* may be moved to the holes *o*.

A stud *p* is threaded into the horizontal wall of the member *h*, and projects freely up through the tool holder *m*. A compression coil spring *q*, and retaining nut *r* form a 60 yielding connection which tends to rock the tool holder *m* on its fulcrum pin *n*.

The tool *s* is fastened in the forward end of the tool-holder by a set screw *t*, and may be used in the position as shown or in a re- 65 versed position.

A rack *u* is supported in the groove *k* of the member *h*, as shown clearly in Fig. 4. This rack is provided with two beveled lugs *v* and *v'* which project up through the slots, 70 *l* and *l'*. Said lugs are not as long as the slots, and thus permit a small longitudinal motion of the rack *u* relative to the member *h*. Plugs *w* and *w'* which have a sliding fit in the slots *l*, are made with horizontal upper 75 faces and beveled lower faces, the latter adapted to match the bevels of the lugs *v*. This arrangement of parts causes the plugs *w* to be lifted vertically upward as the rack moves to the right from its position shown 80 in Fig. 3, and vice versa.

A shaft *x*, having a pinion *y* fixed thereon and in mesh with the rack *u*, is journaled in the frame of the machine. Said shaft may be rotated by hand or by a power ele- 85 ment, whichever is most convenient to the user.

Adjustable screws *z* and *z'* are mounted in the tool holder *m*, and are positioned in vertical alinement with the plugs *w*. 90

The general operation of my machine is as follows:

When the parts are positioned as shown in Fig. 3, the tool is adapted to cut a straight key-way in the work fastened on the face- 95 plate. The shaft *x* is rotated so as to drive the rack and thus the tool in the proper direction.

The initial movement of the rack causes the block *w'* to raise and bear against the 100 end of the screw *z'* so as to rock the tool holder slightly counter clockwise. This action lifts the tool to its cutting position.

Further movement of the rack will cause the tool to perform its cutting operation. A 105 reverse movement of the rack will then cause the block *w'* to drop, thereby permitting the tool holder to rock slightly clockwise and thus draw the tool away from the work to its original position. The depth of cut of 110 the tool may be regulated by the adjusting screw *z'*.

In case it is desired to reverse the tool so as to cut a slot in the lower part of the work, the tool is turned end for end, and the fulcrum pin *n* is changed to the holes *o*. A similar but opposite action of the machine will then be possible.

I claim:

1. In a machine of the character described, a main frame, a horizontally reciprocable slide mounted in said frame, a rack carried by the bottom of said slide, a pinion meshed with said rack, said rack having studs one at each end projecting through holes in the bottom of the slide, said holes being adapted to permit said rack limited sliding motion in said slide, the tops of said studs being beveled and a correspondingly beveled block resting on each stud, a tool holder pivoted in said slide with a screw at each end in said 20 tool holder, said screws adapted for seating on said blocks, yielding means adapted to

hold either of said screws in engagement with its block.

2. In a machine of the character described, a main frame, a horizontally reciprocable slide mounted in said frame, a rack carried by the bottom of said slide, a pinion meshed with said rack, said rack having studs, one at each end, projecting through holes in the bottom of the slide, said holes being adapted to permit said rack limited sliding motion in said slide, a tool holder pivoted in said slide with a screw at each end in said tool holder, said screws adapted for seating on said blocks, yielding means adapted to hold 30 either of said screws in engagement with its block, and means cooperating with said screws in said blocks whereby the reciprocating of said slide will cause a corresponding 35 tilting of the tool holder on its pivot.

CHRISTIAN WINKLER.
